UNITED STATES PATENT OFFICE.

JERMIAH EDWARD CAHILL AND CHARLES FRANCIS JENKINS, OF
WASHINGTON, DISTRICT OF COLUMBIA; SAID JENKINS ASSIGNOR
TO SAID CAHILL.

MOTION-PICTURE MACHINE.

No. 819,514.

Specification of Letters Patent

Patented May 1, 1906

Application filed December 1, 1905. Serial No. 289,936.

To all whom it may concern:

Be it known that we, JERMIAH EDWARD CAHILL and CHARLES FRANCIS JENKINS, citizens of the United States, residing at Washington, District of Columbia, have invented certain new and useful Improvements in Motion-Picture Machines, of which the following is a specification.

Our invention is designed for exhibiting a series of related pictures representing successive phases of an animated scene, commonly known as "motion-pictures," and belongs to that class in which the several pictures are on cards and so moved past the point of observation that each card acts to obscure adjacent cards while the picture thereon is being momentarily exhibited.

The principal object of our invention is to provide means whereby the picture-cards may be closely grouped, giving a great number in a small compass quickly and cheaply assembled and at the same time in a light frame readily interchangeable in the exhibiting-machine.

Figure 1 shows the mechanism in elevation, and Figs. 2 and 3 parts thereof disclosing the method of attaching the picture-cards to the frame.

Fig. 1 shows the cards A in contact at their bases arranged on a ring-like frame B, having internal gear-teeth C supported on and rotated by the pinion D and guided by the grooved roll E. The rotation of the pinion D causes the cards to be bent backward by the detent F, exposing the pictures thereon to view at A'. The continued rotation causes the cards to slip from under the detent F, exposing the next picture in the series, and so on throughout the complete rotation of the frame B, all of which is obvious and readily understood by those skilled in the art to which this invention belongs.

Any suitable means may be employed to fasten the cards to the frame B, although the method we prefer is shown in Figs. 2 and 3— that is, the picture-cards A are perforated at the base with four small holes G. Circularly-bent wires H are inserted in two of these holes, while at the point where the sections of the ring are joined the wire lap or break joints, so that all the holes are occupied at this particular point and for a short distance each way therefrom. One of the sections of the ring is connected up and fitted with the flat plate I, of thin metal or the like, fastened between adjacent sections of the ring-frame by means of the screws J. When this section is filled with picture-cards strung on the curved wires, another section is added, and so on. Four sections are preferred to three, although three are shown in the drawings. The joining of the sections of the frame is done by means of the screws J, and when the last section is put in place the whole forms one continuous picture-card carrier possessing many advantages of construction over any device invented for similar purpose known to us.

What we claim, therefore, as our invention, and wish to protect by Letters Patent of the United States, is—

In motion-picture apparatus, the combination with a set of series picture-cards in register, of a multiple-section ring-like frame, a curved wire attached to each section slightly longer than the section and securing the cards thereto.

In testimony whereof we have affixed our signatures in presence of two witnesses.

JERMIAH EDWARD CAHILL.
CHAS. FRANCIS JENKINS.
